PRODUCTION OF GASOLINE
HYDROCARBONS

Charles F. Teichmann, Mount Vernon, and Arthur R. Goldsby, Beacon, N. Y., Gordon A. Kessler, Ridgewood, N. J., and Max Neuhaus, Bronxville, N. Y., assignors, by mesne assignments, to The Texas Company, New York, N. Y., a corporation of Delaware

Application August 22, 1941, Serial No. 407,984

7 Claims. (Cl. 260—683.5)

This invention relates to production of valuable gasoline hydrocarbons from subterranean distillate reservoirs and particularly to the treatment of low boiling gasoline hydrocarbon constituents of the distillate obtained from such reservoirs.

In its broadest aspect the invention contemplates subjecting the distillate fluid obtained from a distillate reservoir, or suitable fractions of such fluid, to conversion so as to produce gasoline hydrocarbons of improved antiknock value from the distillate. The converted hydrocarbons are removed and the residual gaseous hydrocarbon constituents of the well fluid, including, if desired, gaseous constituents produced in the conversion treatment, are returned under elevated pressure to the subterranean distillate reservoir. Advantageously the conversion is effected under pressure which is not substantially different from that at which the distillate fluid is obtained from the well.

The fluid from subterranean distillate reservoirs is composed mainly of normally gaseous hydrocarbons including methane, ethane and propane. In addition, however, it also contains substantial amounts of normal butane, isobutane, normal pentane, isopentane and other liquefiable hydrocarbons including hexane and heavier. It is customary to subject the fluid from these reservoirs to treatment such as absorption, adsorption and retrograde condensation for the purpose of recovering valuable gasoline hydrocarbons therefrom including butanes and hydrocarbons of higher molecular weight.

The residual gases from which these gasoline hydrocarbons have been recovered are returned under elevated pressure to the reservoir so as to avoid, as far as possible, reduction in pressure in the subterranean formation. Reduction in the formation pressure is usually accompanied by substantial condensation of liquefiable hydrocarbons in the reservoir itself thereby resulting in the permanent loss of useful hydrocarbons. For this reason it is desirable to avoid reduction in the formation pressure.

This condensation which occurs upon reduction of the pressure is known as retrograde condensation. Retrograde condensation, as described in the article by George G. Brown entitled "Retrograde condensation and the critical phenomena," published in the Proceedings of the 18th Annual Convention of the Natural Gasoline Association of America, held May 3-5, 1939, is that condensation which is brought about by reduction in pressure even though the temperature remains constant. As described in this pub-

lication, for every binary or other mixture of normally gaseous hydrocarbons, there is a boundary on the pressure-temperature plane within which two phases exist, namely, a liquid phase and a gas phase, which phases are not of the same composition. At temperatures and pressures outside this two-phase boundary, the hydrocarbon mixture exists as a homogeneous fluid which is regarded as being in the liquid or in the gas phase depending upon the temperature and pressure. Some point on this two-phase boundary represents a critical point at which the liquid and gas phases are of the same composition.

Therefore, if the temperature and pressure of a mixture of hydrocarbons which is already under conditions of temperature and pressure substantially above the critical point, are reduced through the two-phase boundary, retrograde condensation occurs as described in the foregoing publication.

Consequently, it is desirable to return the residual gases, after recovery of the gasoline hydrocarbons, to the reservoir or subterranean formation under elevated pressure so as to maintain the formation pressure and thereby avoid the foregoing condensation of liquefiable hydrocarbons within the formation.

Preferably in accordance with the present invention the well fluid is treated without substantial reduction in pressure so as to convert gasoline hydrocarbons such as normal butane and normal pentane, etc., to gasoline hydrocarbons of improved antiknock value. The converted hydrocarbons are separated from the treated fluid without substantial reduction in pressure and the residual gases then returned to the formation.

The conversion treatment may involve thermal or catalytic reforming at temperatures of about 700 to 1100° F. One advantageous form of treatment comprises hydroforming by contact with a hydroforming catalyst such as a mixture of aluminum and molybdenum oxides or aluminum and chromium oxides at a temperature in the range about 800 to 1000° F. Still another form of treatment comprises isomerization by contact with an isomerization catalyst such as an active metallic halide at a temperature of about 200 to 400° F.

The recovered hydrocarbons including mainly converted hydrocarbons are of improved antiknock value and may be blended with gasoline or may be used as the feed to other conversion processes.

For example, the isobutane formed in an isomerization treatment is advantageously used in an alkylation reaction for reaction with low boiling olefin hydrocarbons to produce normally liq-

uid gasoline hydrocarbons of high antiknock value. Isopentane may be separately reacted with hydrocarbon polymers such as di- and tri-isobutylenes by contact with a suitable alkylation catalyst for the production of safety fuel of high antiknock value.

The temperatures of distillate fluids at the well head are usually of the order of about 100 to 175° F. while the pressures are of the order of about 1000 to 5000 and usually of about 2000 to 3500 pounds per square inch gauge.

In order to effect the desired conversion it is usually necessary to raise the temperature of the well fluid.

For example, where it is desired to effect isomerization of the normal butane contained in the well fluid by contact with an active metallic halide catalyst such as aluminum chloride, it is desirable to effect the isomerization reaction at a temperature of about 200 to 230° F.

Where other types of reactions are employed such as reforming or hydroforming, the temperature may be in the range 600 to 1100° F.

The catalytic conversion is carried out under conditions which are near to or outside the two-phase boundary for the well fluids so that the fluid is substantially entirely in a single homogeneous phase. The conversion reaction may be carried out under temperature and pressure conditions which are somewhat above the critical point for the reacting hydrocarbons, for example, above the critical point for butane and lighter hydrocarbons, so that the pressure upon the hydrocarbon reaction mixture may be subsequently reduced through or within the retrograde condensation range of liquefiable hydrocarbon constituents of the mixture such that substantial condensation occurs. The resulting condensate comprising converted hydrocarbons is separated and the residual gases are thereafter forced back into the subterranean formation.

By effecting the conversion treatment of the hydrocarbons without substantial reduction in the pressure or in other words, at about the pressure corresponding to the pressure of the fluid as obtained from the well, the feed hydrocarbons undergoing treatment are thus in a dense phase during the reaction. This favors more effective contact between the hydrocarbons undergoing conversion and the catalyst. It also permits a higher throughput with a short time of contact.

The well fluid consists mainly of gaseous hydrocarbons, particularly methane. Normal butane may amount to about 1 or 2 mol per cent of the fluid so that the proportion of gaseous material such as methane is relatively large as compared to the content of butane and higher molecular weight hydrocarbons.

The presence of relatively inert gaseous material such as methane in relatively large proportion to the hydrocarbons undergoing conversion is advantageous from the standpoint of inhibiting undesired side reactions and catalyst deterioration during isomerization, for example. It is likewise advantageous in a reforming or hydroforming reaction. In these reactions where substantial cracking occurs some of the gaseous constituents enter into reaction with products of the conversion to form valuable hydrocarbons.

According to one modification of the invention hydrocarbons such as hexane and heavier may be removed and the remaining fluid containing butanes and pentanes then subjected to contact with an isomerization catalyst under conditions such as to effect isomerization of the nor-

mal butane and normal pentane. Removal of the hexane and heavier may be effected by selective absorption, adsorption or by retrograde condensation, and these higher molecular weight hydrocarbons may be subjected to separate conversion treatment or separately disposed of as desired.

In order to describe the invention more fully reference will now be made to the figures of the accompanying drawing.

Referring to Fig. 1, well fluid is obtained from an outlet well 1 tapping a subterranean distillate reservoir.

The fluid is obtained under a pressure, for example, of about 2000 pounds and at a temperature of about 125° F. This fluid may have the following approximate composition:

	Mol per cent
20	Methane ----- 89.46
	Ethane ----- 3.13
	Propane ----- 1.56
	Isobutane ----- 0.74
	Normal butane ----- 0.89
	Isopentane ----- 0.37
25	Pentane ----- 0.48
	Hexane and higher molecular weight hydrocarbons ----- 3.37

Where the fluid is subjected to an isomerization reaction by contact with a catalyst comprising aluminum chloride and hydrogen halide, the well fluid without substantial reduction in pressure is passed through a heat exchanger 2 and heater 3 wherein it is raised to a temperature of about 200 to 250° F. The so heated fluid is then conducted to an isomerization plant 4 wherein the normal paraffin constituents such as normal butane and normal pentane are converted to isoparaffins.

The fluid containing converted hydrocarbons is advantageously passed through pipe 5 to the previously mentioned exchanger 2 wherein it flows in indirect heat exchange relationship with the entering feed. Thereafter it is conducted to a hydrocarbon recovery plant 7 wherein the butanes and higher molecular weight hydrocarbons including converted hydrocarbons are separated from the residual gases. This separation may be effected by absorption in a suitable absorption oil, by adsorption during contact with a solid adsorptive material or by retrograde condensation.

Where the operation is effected by absorption the fluid leaving the catalytic treating plant 4 is cooled to a temperature of about 90 to 100° F. and the cooled fluid subjected to contact with heavy oil, gas oil or other suitable absorption menstruum. The absorption may be carried out either by concurrent or countercurrent contact between the well fluid and the absorption oil, without substantial reduction in pressure and under conditions of temperature and proportion of absorption oil to fluid such that normal butane and higher molecular weight hydrocarbons are selectively absorbed from the residual gases.

Where the separation is effected by adsorption the catalytically treated fluid without substantial reduction in pressure and advantageously after having been cooled to a temperature of about 90 to 100° F. is conducted through a tower packed with a solid adsorptive material such as charcoal or silica gel under conditions such that normal butane and higher molecular weight hydrocarbons are selectively adsorbed in the adsorbent material.

The adsorption operation is advantageously effected in a plant having a plurality of adsorption towers so that while one adsorption tower is on-stream another tower is off-stream for regeneration during which the adsorbed hydrocarbons are stripped from the adsorbent material in the conventional manner.

Where the separation is effected by retrograde condensation this may be accomplished by passing the catalytically treated fluid to a closed vessel wherein the pressure is reduced through or within the retrograde condensation range so that butane and heavier hydrocarbons are condensed.

In any case the residual gases from which the butane and heavier hydrocarbons have been removed are forced by a compressor 8 under elevated pressure through a pipe 9 and returned to an inlet well 10 by which means they are forced back into the subterranean reservoir.

The recovered butane and heavier hydrocarbons are accumulated in a tank 11 for disposition as may be desired, for example, blending with motor fuel stock or for further fractionation to segregate the isoparaffins therefrom for further reaction with olefins to form alkylated hydrocarbons.

The recovered hydrocarbons from the tank 11 may be passed to a fractionator 12 for the purpose of segregating hydrocarbons or fractions therefrom. The recovered hydrocarbons accumulating in the tank 11 may contain substantial amounts of gaseous material which will be released upon reduction of pressure. Accordingly, in the fractionator 12 the overhead fraction may consist essentially of normally gaseous hydrocarbons such as methane, ethane and propane and in addition may include some hydrogen chloride.

The fractionator 12 may be operated to remove a side stream consisting essentially of C₄ or C₅ or a mixture of C₄ and C₅ hydrocarbons rich in isoparaffins; while a residual fraction may be removed consisting essentially of higher boiling hydrocarbons.

The gaseous fraction removed as an overhead from the fractionator 12 is advantageously injected by means of a compressor into the untreated well fluid passing to the catalytic conversion plant 4 and in this way the gaseous hydrocarbons may be ultimately returned to the reservoir while at the same time taking advantage of the promotional effect of the retained hydrogen chloride during the catalytic reaction.

On the other hand, the gaseous fraction may be injected directly to the effluent fluid passing through the pipe 9 for return to the input well. The hydrogen chloride present in the returning residual gases thus serves, upon return to the input well, to open up the formation.

If desired to avoid or substantially reduce the amount of hydrogen chloride passing to the inlet well, the thermally or catalytically treated well fluid may be subjected to scrubbing with water. Thus, the treated mixture flowing through the pipe 6 may be diverted through a branch pipe 13 to a scrubber 14 wherein it is scrubbed with water without substantial reduction in the pressure. In this way the water absorbs substantially all of the hydrogen chloride thereby removing it from the hydrocarbon mixture. The scrubbed hydrocarbon mixture is then returned through a pipe 15 to the pipe 6 for passage to the previously mentioned separator 7.

The water containing absorbed hydrogen chloride is withdrawn from the absorber and may be

disposed of in any suitable manner or may be concentrated in order to recover the acid.

The scrubbing or washing step may be applied following the separation treatment in the separator 7. In other words, the residual gases flowing through the pipe 9 may be subjected to the scrubbing or washing treatment to remove hydrogen chloride.

If instead of subjecting the liquefiable hydrocarbons of the well fluid to the isomerization they are subjected to hydroforming, the method of flow is generally similar to that already described above in connection with Fig. 1 with the exception that the water washing or scrubbing of the treated hydrocarbon mixture is omitted. Thus, the well fluid from the outlet well 1 is passed through the heat exchanger and the heater so as to heat it to a temperature in the range of about 850 to 1050° F. The heated mixture is then passed to the conversion zone 4 wherein it is subjected to contact with a suitable hydroforming catalyst, as, for example, a mixture of aluminum and molybdenum oxides.

Since the feed mixture contains a relatively large proportion of methane there is thus present in the reaction a large amount of hydrogen-containing gas. Provision may be made for recycling hydrogen and hydrogen-containing gases produced in the reaction.

It is contemplated that the well fluid prior to introduction to the catalytic conversion unit 4 may be subjected to chemical treatment such as scrubbing with caustic or other alkali solution for the purpose of removing sulfur compounds and other impurities which if not removed would cause catalyst deterioration in the subsequent catalytic conversion operation.

Referring now to Fig. 2 the well fluid from the outlet well 20 which may be similar to that discharged from outlet well 1 of Fig. 1 and may also be under similar conditions of temperature and pressure, is conducted through a pipe 21 to a separation plant 22 wherein the fluid is separated into fractions, one fraction consisting, for example, of butane and lighter hydrocarbons; and the other fraction consisting of hydrocarbons heavier than butane, namely, pentane and hexane, etc.

This separation may be effected by absorption in a suitable absorption liquid or adsorption by contact with a suitable solid adsorptive material.

The absorption or adsorption operations may be carried out in the conventional manner such as described in connection with similar operations in the recovery plant 7 of Fig. 1. In any case the separation into C₄ and lighter and C₅ and heavier fractions is effected without substantial reduction in pressure. If desired the pressure on the well fluid may be increased so that the separation may be carried out under a higher pressure than that existing at the outlet of well 20.

The C₄ and lighter fraction consisting mainly of methane is passed through a heater or heat exchange apparatus 23 wherein it is raised to the requisite temperature for effecting the subsequent catalytic conversion, in this case isomerization. The heated fluid is then passed through a catalytic conversion unit 24, wherein the normal butane is subjected to contact with an isomerization catalyst maintained under isomerizing conditions, but without substantial reduction in pressure of the well fluid.

The catalytically treated fluid is then passed to a separation or recovery unit 25 similar to the recovery unit 7 of Fig. 1, and by which means C₄

and heavier hydrocarbons are separated and recovered from the residual gases. The residual gases are thereafter forced by means of a pump or compressor 26 into an input well 27 for return to the subterranean formation.

The recovered C₄ and heavier fraction is passed to a storage tank 28. The recovered fraction may be disposed of as described in connection with the liquid accumulating in tank 11 in Fig. 1.

The C₅ and heavier fraction removed from the separation unit 22 is passed to a storage tank 29 and may be disposed of as blending stock for gasoline. Advantageously, however, it is subjected to a catalytic conversion treatment such as previously disclosed. In such case the fraction is conducted from the tank 29 to a separate conversion unit 30 wherein it is subjected to the conversion treatment.

The resulting converted hydrocarbons rich in isoparaffins can then be used as a blending stock or can be fractionated to segregate individual hydrocarbons or hydrocarbon fractions therefrom for such further disposition as may be desired.

While reforming and isomerization have been mentioned in connection with the catalytic conversion of readily liquefiable hydrocarbons of the well fluid, nevertheless it is contemplated that the conversion treatment may comprise other desired types of conversion reactions either catalytic or pyrolytic such as cracking and dehydrogenation, for example, in order to obtain the desired type of converted hydrocarbon products. More elevated temperatures are usually required where a cracking type of operation is employed, and the catalysts used may be aluminum silicates, natural or artificial, or silicate or other solid adsorptive materials impregnated with metals and metal compounds.

Where a simple isomerization reaction is involved the catalyst is advantageously one selected from the group of metallic halides such as aluminum chloride, iron chloride, zirconium chloride, metallic mixed halides such as aluminum chlorofluoride (AlClF₂), aluminum fluorochloride (AlFCl₂) and the like, promoted with a hydrogen halide such as hydrogen chloride.

Under certain conditions a promoter may not be required, for example, in the isomerization of pentane and the like with a metallic mixed halide catalyst.

The isomerization of the normally liquid fraction accumulating in the tank 29 of Fig. 2 is advantageously effected in the liquid phase using a solid metallic halide catalyst dissolved or suspended in metallic halide-hydrocarbon complex. Moreover, the reaction is advantageously effected in the presence of an extraneous material such as hydrogen, methane, ethane, isobutane, etc., or a naphthalene hydrocarbon, namely, cyclopentane, cyclohexane, etc., for the purpose of inhibiting cracking of hydrocarbons and deterioration of the catalyst. For example a portion of the residual gases from the reaction in conversion zone 24 may be mixed with the hydrocarbon feed to the isomerization reaction in conversion zone 30.

Provision may be made for recycling hydrogen and hydrogen-containing gases, formed in the conversion, through the conversion reaction zone as described in connection with Fig. 1. Moreover the conversion in unit 30 may be carried out under pressure corresponding substantially to that of the well fluid at the head of the outlet well.

Provision may be made for altering the pressure prevailing at any stage in the process. For example, in the absorption or adsorption opera-

tions the pressure may be adjusted, depending upon temperature and other conditions, in order to obtain the desired separation. If it is necessary to reduce the pressure, then provision must be made for increasing the pressure in a later stage or stages of the process in order to force the residual gases back into the inlet well. Advantageously a substantial reduction in overall pressure is avoided so as to reduce the amount

10 of compression required in order to return the residual gases to the subterranean reservoir.

While return of residual gases to the same reservoir has been described, it is contemplated that they may be returned, all or in part, to a different or neighboring subterranean reservoir for the purpose of maintaining or aiding in maintaining reservoir pressure.

Obviously many modifications and variations of the invention, as hereinbefore set forth, may be made without departing from the spirit and scope thereof, and therefore only such limitations should be imposed as are indicated in the appended claims.

We claim:

25 1. A process of producing low boiling gasoline hydrocarbons of improved antiknock value from the well fluid of a subterranean distillate reservoir which comprises obtaining well fluid from an outlet well of the reservoir at a high well head

30 pressure, said fluid containing gaseous hydrocarbons having 4 carbon atoms and less per molecule and higher molecular weight hydrocarbons having 5 and more carbon atoms per molecule, removing said higher molecular weight hydrocarbons from said fluid without substantial reduction in pressure, and then subjecting the residual fluid while at substantially well head pressure to contact with an isomerization catalyst in the presence of hydrogen halide at an elevated tem-

35 perature in the range below about 400° F. such that substantial isomerization of normal paraffin constituents of the residual fluid to isoparaffins occurs, thereafter separating from said residual fluid containing isomerized hydrocarbons and hydrogen halide at pressures within the retrograde condensation range a hydrocarbon condensate, removing the resulting condensate from residual gas and recycling residual gas containing hydrogen halide to an inlet well of said reservoir.

40 2. A process of producing low boiling gasoline hydrocarbons of improved antiknock value from the well fluid of a subterranean distillate reservoir which comprises obtaining well fluid from an outlet well of the reservoir at a high well head

45 pressure said fluid containing gaseous hydrocarbons having less than 4 carbon atoms per molecule and higher molecular weight hydrocarbons having 4 and more carbon atoms per molecule, separating from said fluid without substantial reduction in pressure a fraction comprising C₄ hydrocarbons and lighter constituents of the fluid, subjecting said C₄ and lighter fraction while under substantially well head pressure to contact with an isomerization catalyst maintained in the presence of hydrogen halide at an elevated tem-

50 perature in the range below about 400° F. such that substantial isomerization of normal butane to isobutane occurs, passing the isomerized fraction containing some hydrogen halide to a sep-

55 arating zone, effecting separation therein of a hydrocarbon condensate without substantial reduction in pressure, removing the resulting condensate from residual gas and recycling residual gas containing hydrogen halide to an inlet well of said reservoir.

3. A process of producing low boiling gasoline hydrocarbons of improved antiknock value from the well fluid of a subterranean distillate reservoir which comprises obtaining well fluid from an outlet well of the reservoir at a high well head pressure, said fluid containing gaseous hydrocarbons having less than 4 carbon atoms per molecule and higher molecular weight hydrocarbons having 4 and more carbon atoms per molecule, separating said fluid without substantial reduction in pressure into a fraction comprising C₄ hydrocarbon and lighter constituents of the fluid and a fraction comprising higher molecular weight hydrocarbons, subjecting said C₄ and lighter fraction while under substantially well head pressure to contact with an isomerization catalyst maintained in the presence of hydrogen halide at an elevated temperature in the range below about 400° F. such that substantial isomerization of normal butane to isobutane occurs, passing the isomerized fraction containing some hydrogen halide to a separating zone, effecting separation therein of a hydrocarbon condensate without substantial reduction in pressure, removing the resulting condensate from the residual gas, separately subjecting said higher molecular weight fraction to an elevated temperature in the range 700 to 1100° F. whereby said hydrocarbons undergo conversion into hydrocarbons of improved character for gasoline manufacture and some gas, removing the gasoline hydrocarbons from the products of said conversion and recycling the residual gas containing hydrogen halide from the isomerization reaction and the conversion reaction to an inlet well of said reservoir.

4. A process for recovering hydrocarbons from high pressure well fluid which comprises obtaining well fluid from an outlet well of a subterranean formation, said fluid containing gaseous hydrocarbons having 4 carbon atoms and less per molecule and some higher molecular weight hydrocarbons, removing said higher molecular weight hydrocarbons from the residual fluid, subjecting the residual fluid to contact with an isomerization catalyst in the presence of hydrogen halide at an elevated temperature not exceeding about 400° F., such that substantial isomerization of C₄ hydrocarbon occurs, passing the catalytically treated fluid containing some hydrogen halide to a separating zone, effecting separation therein of a hydrocarbon condensate, removing said condensate from the residual gas containing hydrogen halide, and recycling said residual gas containing hydrogen halide to an inlet well of said formation.

5. A process for recovering hydrocarbons from high pressure well fluid containing gaseous and liquefiable hydrocarbons including normal paraf-

fins, which comprises flowing said fluid from an outlet well of a subterranean formation, subjecting normally gaseous and liquefiable hydrocarbon constituents of said fluid to contact with an isomerization catalyst in the presence of hydrogen halide at an elevated temperature such that substantial isomerization of normal paraffin hydrocarbons occurs, passing resulting catalytically treated hydrocarbons containing some hydrogen halide to a separation zone, effecting separation therein of a hydrocarbon condensate, removing said condensate from residual gas containing hydrogen halide, and recycling said residual gas containing hydrogen halide to an inlet well of said formation.

6. A process for recovering hydrocarbons from high pressure well fluid containing gaseous and liquefiable hydrocarbons including normal paraffins, which comprises flowing said fluid from an outlet well of a subterranean formation, subjecting normally gaseous and liquefiable hydrocarbon constituents of said fluid to contact with a metallic halide catalyst in the presence of hydrogen halide at an elevated temperature not exceeding about 400° F., passing resulting catalytically treated hydrocarbons containing some hydrogen halide to a separation zone, effecting separation therein of a hydrocarbon condensate, removing said condensate from residual gas containing hydrogen halide, and recycling said residual gas containing hydrogen halide to an inlet well of said formation.

7. A process for recovering hydrocarbons from high pressure well fluid containing gaseous and liquefiable hydrocarbons including normal paraffins which comprises flowing said well fluid from an outlet well of a subterranean formation, subjecting normally gaseous and liquefiable hydrocarbon constituents of said fluid to contact with an isomerization catalyst in the presence of hydrogen halide at an elevated temperature such that substantial isomerization of normal paraffins occurs, passing resulting catalytically treated hydrocarbons containing hydrogen halide to a separating zone, effecting separation therein from residual gas of a hydrocarbon condensate containing some normally gaseous constituents including hydrogen halide, removing said condensate from residual gas, subjecting the removed condensate to fractionation into a normally gaseous fraction containing some hydrogen halide and a higher boiling fraction, removing the higher boiling fraction and recycling residual gas and said normally gaseous fraction containing hydrogen halide to an inlet well of said formation.
